GAME

Clifton S. Sultzer, Red Wing, Minn., assignor to
Louise E. Sultzer, Red Wing, Minn.

Application March 22, 1935, Serial No. 12,393

5 Claims. (Cl. 116—120)

My invention relates to an improvement in games of a type designed for use by a player hearing the description of a football game or the like, broadcast over the radio.

5 In listening to the broadcast of a football game over the radio, the listener is often times confused by the terms used by the announcer. It is also a fact that the game is often less interesting through the lack of a pictorial view of the 10 position of the ball on the playing field. It is often found that the information broadcast by the radio announcer provides more detailed information on the events taking place than are observed by the usual spectator. However, if 15 the listener to a broadcast cannot actually see the position of the ball on the playing field, the game often lacks the interest it would otherwise have. In order to graphically show the position of the ball on the playing field, large charts are 20 sometimes prepared by which a listener may mark the progress of the game with the use of certain predetermined symbols. Such a chart, however, is difficult to form and somewhat of a knowledge of a game is necessary in order to keep 25 accurate records.

It is an object of my invention to provide a folder containing a chart illustrating a playing field and to provide a simple adjustable means to disclose the position of the ball at all times. My 30 invention also provides a means of disclosing at a glance the number of yards which have been made and which remain to be made in any series of downs.

In preferred form, my invention comprises a 35 pair of guides mounted longitudinally along a chart of a playing field and to mount upon these guides markers to denote the position of the ball at any time and to disclose the yards made or remaining to be made in any series of downs.

40 It is a feature of my invention to provide in combination with the playing field, a chart in which the records of the game may be accurately kept. The adjustable markers used in combination with the playing field may be readily ad- 45 justed with the end of a pencil and the pencil may be used also to mark down the records of the essential statistics of the game.

It is also a feature of my invention to provide 50 in combination with a chart disclosing a playing field and diagram for use in following a football radio broadcast, charts showing the usual common forms of offense and defense used in modern day football. By this means the listener may readily note the various forms of line-up which 55 may be described by the radio announcer so that

the listener may more readily understand the game.

These and other objects and novel features of my invention will be more fully and clearly set forth in the following specification and claims. 6

In the drawing forming part of the specification:

Figure 1 discloses my folder in partially opened form in the position it might assume while being used to record a football broadcast. 10

Figure 2 discloses the reverse sides of the folder laid out in flat formation.

Figure 3 is a section on the line 3—3 of Figure 1.

Figure 4 is a sectional view similar to Figure 3, 15 disclosing an alternative form of construction.

Figure 5 is a detail view of a corner of my folder, disclosing a pad of record sheets which may be used rather than the single sheet of the folder illustrated in Figure 1. 20

The folder A comprises a front cover 10, a record second page 11, a third page 12 illustrating diagrammatically a football field, and a rear page 13 on which appears various rules and formations to clarify the broadcast. The cover 25 10 merely provides a decoration for the folder and may comprise an advertisement for a product as disclosed.

The record sheet 11 comprising the second page of the folder is preferably formed as disclosed and is divided into various sections 14, each of which comprises a complete space for records of a single game. The sheet 11 disclosed in Figure 1 has, for example, nine sections 14 for keeping records of nine games during a season. 35 This number of sections has been chosen as most amateur football teams do not play more than nine games during the football season, so that the sheet 11 would form a complete record of the year of every game. Obviously, the number 40 of sections 14 on the sheet 11 may be varied at will.

In each of the sections 14 columns 15 are provided for recording the name of the team playing and recording separately statistics from each 45 period of the game as well as the total for all of the periods. The statistics which are listed are written in horizontal columns defined by transversely extending lines 16 and may include any statistics usually recorded from a game such as 50 the number of first downs, the number of fumbles, the number of forward passes completed, the score, and the like.

The third sheet of the folder A, designated by the numeral 12 on the drawing, illustrates a 55

playing field 17 which is divided by transversely extending lines 18 simulating the yard lines on a football field. These lines 18 are equi-distant apart, and the distance between adjacent lines represents ten yards on the playing field. Lighter lines 19, midway between the lines 18, represent five yard lines. Even lighter lines 20 can be provided if desired, to represent each yard along the field. Suitable indicia 22 along the 5 sides of the playing field 17 designate the various lines, so that any yard line along the playing field may be readily found in a minimum of time.

At either end of the playing field 17, I provide an arcuate cut 23 which forms a pair of oppositely 10 disposed ears 24. A fine wire 25 is looped under one of these ears 24, extended the length of the playing field 17, and is fastened beneath the other ear 24. In this manner I provide a pair of fine wires stretched tightly the length of the playing field 17 in parallel relationship. On one of the parallel wires I provide a tube 26 of composition, metal, paper or any suitable material, which is just the length of the distance between the ten yard marking lines 18. This tube 26 represents the ten yard chain of the head linesman; and one end of the tube is set at the point where the ball is set in play for a series of downs and clearly illustrates at all times the number of yards made in a series of downs, and the yards yet 15 to be made in a series of downs to make a first down.

On the other parallel stretch of the wire 25, I provide a bead 27 which is slideable along this wire to any point on the playing field. This bead 27 simulates the ball, and is moved back and forth 20 along the field as the game is played, showing at all times the exact position of the ball on the playing field. The tube 26 and bead 27 are drawn into engagement with the board by the tightness of 25 the wires.

In listening to the radio broadcast, the announcer first will describe the kick-off. The ball is placed on the forty yard line for this play; and the listener slides the bead 27 to the forty yard 30 line. After the ball is kicked, it is picked up by the opposing team, and run out to, for example, the twenty-two yard line. The bead is then adjusted to the opposite twenty-two yard line, and the tube 26 is moved along the wire 25 until the 35 end thereof nearest the adjacent goal line is on the twenty-two yard line. Say, for example, that on the first down the team with the ball runs the ball to the twenty-seven yard line, for a gain for five yards. The bead 27 is moved to the twenty-seven yard line; the tube 26 remaining in the 40 previously adjusted position. This is the position of the ball in Figure 1 of the drawing. In this figure, the team defending the left goal has possession of the ball, and it may be seen at a glance that the team has five yards to go for a first 45 down. The tube 26 is only moved when one team or the other has possession of the ball for a first down.

As first down, or forward passes are made, or 50 the ball is fumbled, or scores are made, these statistics are recorded in the sections 14 of page two of the folder, designated by the numeral 11. In this manner a record of the game may be kept for future use.

70 The fourth page of the folder A, designated by the numeral 13, illustrates diagrammatically several playing fields 28 on which are arranged diagrammatically the various common offensive and defensive arrangements of players. Each playing field illustrates a common offensive line-up, and

5 a common defensive arrangement. Thus when the radio announcer describes certain formations which the players are assuming on the field, the listener may at a glance note the arrangement of which the announcer speaks. A better picture of the game may in this way be obtained. For example, when the announcer speaks of a 6-2-2-1 arrangement of a defensive team, the actual 10 positions of the various players can be seen.

On the sheet 13 of the folder A, I may also describe various rules and explanation of points of the game, for the purpose of clarifying the game in the minds of the listeners. A list of penalties and the reasons for such penalties may 15 be provided. A playing field illustrating the arrangement of the players for a kick-off designated in Figure 2 by the numeral 28, may also be provided.

I have described my folder as comprising a single folded sheet. It may be desirable in some 20 instances, to provide a pad 29 of sheets, as illustrated in Figure 5, to make the folder accommodate a greater number of game records. In this modification, a pad 29 of sheets is merely secured to the page 11 of the folder A, each sheet 25 bearing forms for containing records of one or more games.

Figure 4 illustrates a slightly different form of support for holding the wire 25 stretched across the playing field. In this form, a metal clip 30 is 30 provided, having a body portion 32, pointed ears 33 which extend through the folder A and are clinched over on the opposite side of the sheet, and a hook tongue 34 within which the wire 25 is looped. Other means may be provided, as well 35 as those specifically shown, for holding the wire 25 in position longitudinally across the playing field 17.

If desired, my bead may be in the form illustrated in Figure 4 of the drawing. In this modification, the bead 35 is square in shape, and the various sides 36 and 37 are differently colored. By turning the bead so that one color is displayed 40 while one team is in possession of the ball, and so that another color is displayed while the other team is in possession of the ball, the direction of travel of the ball may at all times be noted. It will be noted that one face of the bead 35 engages the playing field 17 while the opposed surface is 45 displayed, preventing rotation of the bead until 50 desired.

I have provided a game which may be played in co-ordination with a football radio broadcast. This game illustrates at all times the position of the ball and the yards which must be made for 55 a first down. My game thus provides a visible means of showing the exact position of the ball on the playing field, and is used in combination with a record sheet for statistics, and with an explanation for doubtful points of the game. 60

In accordance with the patent statutes, I have described the principles of operation of my game, and while I have endeavored to set forth the best embodiment thereof, I desire to have it understood that this is only illustrative of a means of carrying out my invention, and that obvious 65 changes may be made within the scope of the following claims without departing from the spirit of my invention.

I claim:

1. A game including a playing field, simulating a football field, a guide extending longitudinally of said field, slideable and rotatable polygonal means on said guide for indicating the position of a ball on the field in accordance with the 70 75

position of a ball on the field of a game being broadcast, and means on said slideable means made visible by rotating said rotatable and slideable means for indicating which team is in possession of the ball.

5 2. A game board including a base board, a pair of clips each anchored in said base board and having a body portion overlying a portion of said board, a spring tongue doubled back from said body portion to form a normally closed hook, a loop extending between said clips and anchored in said hooks formed by said tongues, and a slideable and rotatable indicator having indicia bearing flat sides mounted on said loop.

10 10 3. A game board including a base board, a loop stretched over said game board and anchored at opposite ends, and a cubicular slideable member slidably mounted on one side of said loop and slideable between said opposite ends of said game board, one surface thereof engaging said base board to prevent rotation thereof unless desired, said cubicular member bearing indicia on some 20 of its sides.

20 4. A game board including a base board,

tongues formed in said base board defined by slots in said board, said slots terminating along parallel lines, a loop extending beneath said tongues and extending over the game board between said tongues, and a slideable and rotatable indicator having indicia bearing flat sides mounted on said loop. 5

5 5 6. A game device comprising a sheet of foldable material, a portion of said foldable sheet having a pair of oppositely disposed arcuated 10 slots therein, said slots providing arcuated tongues each having a thickness corresponding to the entire thickness of the sheet portion, the free ends of said tongues extending in opposite directions, and the sheet portion providing a 15 continuously flat surface between said tongues, a loop extending over the foldable sheet portion between said slots, said loop extending through one end of each slot, beneath the tongue within said slot, and through the other end of each slot, 20 and a slideable indicator on said loop, said indicator being held in engagement with the foldable sheet by said loop.
